UNITED STATES PATENT OFFICE.

WILLIAM A. SOMMERHOF, OF ERIE, PENNSYLVANIA.

DESIGN FOR AN ARTICLE OF MANUFACTURE—NAMELY, A SCREEN FOR SOUND-OUTLETS
OF GRAPHOPHONES.

53,617.

Specification for Design.

Patented July 15, 1919.

Application filed November 19, 1918. Serial No. 263,226. Term of patent 14 years.

To all whom it may concern:

Be it known that I, WILLIAM A. SOMMERHOF, a citizen of the United States, residing at Erie, in the county of Erie and State of Pennsylvania, have invented a new, original, and ornamental Design for an Article of Manufacture—namely, a Screen for Sound-Outlets of Graphophones—of which the following is a specification, reference being had to the accompanying drawing, forming part thereof.

Copies of this patent may be obtained for five cents each, by addressing the "Commissioner of Patents, Washington, D. C."

The figure is a plan view of a screen for sound outlets of graphophones, showing my new design.

I claim:

The ornamental design for an article of manufacture, namely a screen for sound outlets of graphophones, as shown.

WILLIAM A. SOMMERHOF.
